(57) **CLAIM**

The ornamental design for a vehicle side bumper, as shown and described.

DESCRIPTION

FIG. 1 is a front perspective view of a first embodiment of a vehicle side bumper showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front perspective view of a second embodiment of a vehicle side bumper showing our new design;

FIG. 9 is a front elevational view of FIG. 8;

FIG. 10 is a rear elevational view of FIG. 8;

FIG. 11 is a top plan view of FIG. 8;

FIG. 12 is a bottom plan view of FIG. 8;

FIG. 13 is a left side elevational view of FIG. 8; and,

FIG. 14 is a right side elevational view of FIG. 8.

The broken lines illustrated in FIGS. 1 and 8 are for illustrative purposes only and form no part of the claim design.
